UNITED STATES PATENT OFFICE

AUGUSTO ARANCIBIA, OF VALPARAISO, CHILE

PLIABLE WIRE MATTRESS

Application filed October 24, 1927. Serial No. 228,354.

This invention is directed to an improvement in spring bed bottoms of the wire web type, being more particularly directed to a bed bottom of this character made up of relatively movable parts adapted to be folded into a comparatively compact form for shipment and storage.

The primary object of the invention is the provision of a folding bed bottom including a central section and end sections having hinged connection with the central section, means being provided to secure the alignment of the respective sections when in opened relation.

15 The invention further provides a bracket which is secured to the side rails of the central section and supports transverse rails in a position below the side rails a sufficient distance to permit the free swinging of the wire bed bottom.

20 The invention further provides for securing the edges of the wire web to the side rails in a manner to conveniently secure it in place and protect it from tearing.

25 The invention is illustrated in the accompanying drawings, in which:

Figure 1 is a side elevation of the complete frame of the independent wire web bottom of my invention.

30 Figure 2 is a plan view of the same showing clearly the central and two end sections of the frame extended.

Figure 3 is a detail transverse section on line 3—3 of Figure 2.

35 Figure 4 is a detail transverse section on the line 4—4 of Figure 2.

Figure 5 is a side elevation of the bed bottom in folded relation.

40 Figure 6 is a detail side elevation of the hinge connection between the sections, parts being shown in section.

Figure 7 is a detail perspective view on a larger scale of a part of the hinge connection between the sections.

Figure 8 is a detail perspective view of the complementary hinge connection.

Figure 9 is a detail section showing the manner of securing the wire web to the side rails in the three sections of the folding mattress.

In the drawings, 1 represents the central section of the folding mattress; 2, 2 the foldable end sections of the same; 3 the hinges connecting the central and end sections; 4 indicates transverse rails on the ends of which are riveted brackets 13 the upper ends of the latter being welded to the side rails 1^a of the central section of brackets 13; 5, 5 are cross members welded to the foldable end sections 2, 2, which serve to guide the ends over the rails 14 of the bedstead frame. On the inner ends of the side rails of the end sections are depending plates, each of which is provided with a stud 7 which engages in openings 8, formed in the brackets 13 when the mattress is in use. 9 indicates the wire web bottom having its edges bent over and soldered to reinforce it. Plates 12 clamp the web against the rails of the sections, the plates being held in position by means of bolts 11 passing through openings 6.

If desired brackets, similar to brackets 13 may be used to connect the cross members 5 to properly space same from the bed, thus lending stability to the mattress over the bedstead. In use, the cross bars 4 are fitted between the side rails 14 of the bed, the end portions of the brackets 13 resting on the upper surface of the rails, as shown in Fig. 7. When the end sections are in the same horizontal section as the central section, the studs 7 engage in the openings 8, and the brackets on the adjacent sections abut, thus holding the sections in alignment.

When the mattress is not in use, the two end sections are folded over the central section as shown in Fig. 5, thus economizing space.

What is claimed to be new is:

In a folding bed bottom, a central section, end sections, hinges connecting the end sections to the central section, abutting plates carried at each end of the hinged sections,
5 one of said plates being formed with a hole, a pin projecting from the other plate and adapted to fit the hole when the sections are extended to thereby maintain the alignment of the sections, and cross rails secured to the
10 central section arranged below the plane of such section, the end plates being extended to provide supports for said rails.

In testimony whereof I affix my signature.
AUGUSTO ARANCIBIA.
